EYESHIELD

Gray Miller, Jr., Westmount, Quebec, Canada

Application December 2, 1938, Serial No. 243,670
In Canada April 1, 1938

5 Claims. (CL 2-12)

This invention relates to an improved eyeshield.

Eye protection

Devices of this nature become important as increasing attention is being paid to the protection of eyes particularly in outdoor pursuits where the elements such as glare, wind, dust and snow are unavoidably encountered. In high speed activities as for instance in sports like skiing, bob sled and automobile racing, motor cycling, and in water sports, particular factors are encountered which reduce the utility of conventional devices owing to their inability to give satisfactory protection. Many types of glasses, goggles, shields and other protective devices which have been developed specially to cope with these conditions are also inadequate in certain respects.

In skiing possibly the main source of eye strain is glare from the sun shining on the snow, for which a tinted shield or goggles are desirable. Then, in downhill running where considerable wind resistance is developed, unless the goggles or shield are such that the head wind is properly deflected, wind and snow get in the eyes causing serious inconvenience. The majority of goggles and shields which are useful in protection against these conditions to a greater or lesser degree, are worn close to the face and suffer from lack of ventilation causing them to fog or cloud with moisture, which condenses under varying temperature conditions. For instance, when the skier is going up hill where the wind is usually cut off, his warm moist breath rising on to the cold surface of the goggles, causes condensation, the consequent cloud-up resulting in the obliteration of his vision. Condensation may also be caused by warm moist air from the eyes being trapped and condensed on the inside of the goggles. This being the case, clouding may have occurred to such an extent on reaching the top of the hill that it is almost essential to wipe off the moisture before descent. In racing, however, the skier cannot conveniently stop, and when his goggles cloud is frequently forced to continue under seriously impaired visual conditions.

Furthermore, goggles of the types now in use are usually closed in at the edges and ventilated through orifices or a screen, and fit close to the eyes thus providing little air space. They are found particularly uncomfortable since the air has not sufficient chance to circulate and heats up, causing the eyes to burn. Lack of ventilation also allows fogging when changes of temperature are encountered or the wearer's breath rises on to their surface.

Objects

With the foregoing in mind, it is an object of the present invention to provide in a shield for various purposes the two essential requirements to eye comfort, adequate protection and unimpaired vision. A further object is to provide a shield of this nature, constructed for complete ventilation so as to prevent clouding or fogging. A still further object is to provide a device of this nature which is extremely light, flexible, non-shatterable and convenient to wear or to carry.

Improved shield

With these objects in view a feature of the improved shield is a transparent and flexible body portion like an inverted visor, and sufficiently extensive for unobstructed vision. A bottom edge, held in place by an elastic head band, fits snugly to the nose and cheeks well below the line of vision. The body portion extends outwards toward the upper edge, which lies well out from the forehead and from the side face to provide a large air space for ventilation. Worn in this manner, the shield presents a streamlined surface to divert wind to either side and downwards, without reaching the eyes. Eddies or top drafts entering the space between the forehead and top of the shield emerge through the opening between the top of the shield and the side face carrying with them any snow or dust which may have fallen in.

Drawings

The invention will be best understood by reference to the accompanying drawings illustrating a preferred embodiment, and in which,

Figure 1 is a plan view of one form of shield, constructed according to the present invention, laid out flat to show its structural features.

Figure 2 is a plan view of another form of shield, constructed according to the present invention, and laid out flat.

Figure 3 is a perspective view of the shield shown in Figure 2, in position on the wearer's face.

Figure 4 is an enlarged plan view looking down from the top edge of the shield in position as shown in Figure 3.

Figure 5 is a cross section along the line 5-5 of Figure 2.

Figure 6 is a lower corner view of the opposite side of the shield from that shown in Figure 2, showing especially a method of connecting the head band to the body portion.

Detailed description

Referring more specifically to the drawings, the form of shield illustrated in Figure 1 includes a body portion 11, of non-shatterable and non-inflammable transparent flexible material suitable for devices of this general nature, coloured or tinted if desired. The body portion 11 has a lower edge 12, a top edge 13 and side edges 14. The lower edge 12 is provided with a narrow binding 15 and is shaped to fit the wearer's features, having a deep nose recess 16 and shallow cheek conforming portions 17. For purposes to be described later in detail, when the body portion is laid flat the outside ends of the lower edge 15 are substantially lower than the projecting inner portion of the bottom edge adjoining the nose opening, so that the ends and inner portion are on an inwardly extending arc. That is to say, the cheek-conforming portions are lower towards their outer ends than towards the middle of the shield so that when the lower edge is drawn tightly against the face the upper part of the shield is caused to buckle.

The contour of the upper edge is an outwardly extending arc of greater curvature than that of the lower edge, while the side edges 14 joining the upper and lower edges are substantially straight. A head band 18 is joined to the body portion at points adjacent the junction of the lower and side edges.

A modified form of shield is illustrated in Figures 2 to 6. In this form, the shield comprises a body portion 30 being a sheet of suitable flexible transparent material, the body portion being not so long and of somewhat different shape to the form illustrated in Figure 1, and the top edge being straighter. The lower edge is substantially of the shape indicated in the drawings and is provided with a binding in the form of a suitably secured and projecting leather strip 31, which is slit at 31a as illustrated, to render the binding flexible to assume the contour of the face when resting against it. For some uses the edge of the shield adjacent the nose may be made without the strip 31, so that there will be absolutely no obstruction to free vision. A nasal bridge similar to those used on eyeglasses may be employed if desired. The top edge of the body portion 30 is provided with a reinforcing element 32, which may either be, as in the form illustrated, a strip comprising another layer of material similar to that of the body portion, or a corrugation in the material itself, or any other device which will serve the purpose of rendering the top edge stiffer than the remainder of the body portion.

The lower corners of the body portion are provided with spaced-apart eyelets 40 through which passes a lace 41 connected to the end of an elastic head band 42 of adjustable length. Through this means of connection the head band 42 may, when the shield is in place, be moved up and down between the eyelets, thus engaging the point of tension of the head band in relation to the shield when on the wearer's head, and causing adjustment of the angle which the shield assumes to the face.

Both the shield form illustrated in Figures 2 to 6 and the other form illustrated in Figure 1 are put on by passing the head band about the head and placing the specially contoured lower edge of the shield against the wearer's features.

In either form of the shield, the reinforced edge of the nose recess fits relatively low down on the nose as compared with goggles or similar

devices thus doing away with the obstruction to vision which is so common at this point. Also the cheek edges of the binding rest relatively low down on the cheeks, engaging the latter usually just below the curve of the cheek bone, the remaining outside portions of the lower edges passing across the side face to meet the head band. Thus the lower edge of the shield is well below the line of vision. The particular contour of the lower edge when it is against the face causes the remainder of the upper body portion to buckle outwards, something like an inverted visor, forming between it and the head an air space for ventilation and at the same time presenting a streamlined surface.

In the case of the alternate form of shield described in Figure 2 and following, the reinforcing or stiffening element has as its primary function the elimination of undesirable reflection from the sun shining down into the top of the shield, sometimes occurring in the use of the model of Figure 1. The stiffening effect of this element changes the contour of the body portion when the latter is flexed into position on the wearer's head, doing away with any extreme flare forward caused by the buckling of the shield as a result of the curvature of the face edge when urged against the face.

The consequent reduction of angle of incidence of possible sun's rays, with an equal reduction of the angle of reflection, causes all light rays reflected from above, to strike below the eyes and not into them. The net result is the elimination of glare or reflection on the inside surface of the shield.

The secondary function of the reinforcing element is to act as a frame for the shield enabling it to maintain a desirable contour even against the pressure of a strong head wind.

In this way, the conformation of the shield when in position is particularly important in overcoming wind conditions and in providing ventilation. A stiff head wind, as for instance in downhill skiing, is deflected by the surface of the shield to each side and downwards. The top of the shield, being open, permits adequate ventilation of the inner surface maintaining it at the same temperature as the outer surface, thus preventing the collection of moisture upon either. Light currents of air are found to circulate downwards between the top of the shield and the head, and out through the gap formed between the sides of the shield and face, thus further ventilating the inside surface to keep it free from moisture.

The open top of the shield allows any warm air of the face to arise from it, and prevents overheating of the eyes with the resultant smarting, a fault common to most eye protectors.

The expanse of the body portion and the low position of the binding well down on the face below the line of vision permit an unobstructed view. The low fit also permits the specially constructed binding to rest on a relatively flat portion of the face rendering the shield extremely difficult to dislodge. The tension of the headband maintains the free edge firmly in position and at the same time by reason of the latter's contour, as already described, causes the upper portion of the shield to fan outwardly so as to present a streamlined surface and to provide a large unenclosed air space for ventilation. A further surprising feature of this air space is that under most conditions when the wearer is moving or the wind is blowing the gentle air

currents caused to flow therethrough by the conformation of the shield carry falling snow or dust to the rear and away from the eyes.

The flexible and non-shatterable nature of the material from which the body portion is constructed renders it safe to use. When in position the large space formed between the face and the shield permits it to be worn over glasses.

While preferred forms of the shield have been illustrated in which large integral and flexible body portions are provided, it will be understood that the invention permits of variations and alternative forms. For instance, the shield may be of molded material shaped to fit the face and to provide the expansive air space for ventilation purposes. Conceivably, a modified form might be in two sections, one for each eye, like goggles, providing an open top is formed adequate for the purpose of ventilation. The head band may, if desired, be replaced by ear-engaging arms such as those commonly used with eyeglasses. When the shield is being used purely to guard the eyes from sun and glare, and added ventilation is desirable, small ventilating orifices can be provided in the body portion just above the binding on the face edge. Other trade variants can naturally be employed to render the shield most efficient. Various other modifications may be made in the structure without departing from the spirit of the invention.

The sub-titles used throughout the specification are merely to simplify reference thereto and should otherwise be disregarded.

I claim:

35 1. A frameless, flexible eyeshield requiring contact with the features to be held in operative shape and in position, comprising, a flat expansive sheet of transparent material constituting the body portion, the lower edge of said sheet being shaped to include a nose recess and cheek-conforming portions adapting it to fit the face below the eyes; on flexure into contact therewith, said cheek-conforming portions being lower towards their outer ends than towards the middle of the shield, whereby the upper part of the sheet is buckled outwards to provide an open top for ventilation when the lower edge is urged against the features, retaining means secured to the outer corners of the lower edge for urging said lower edge against the features to hold the shield in operative shape and in position, and a transparent flexible stiffening member secured to the top edge of said sheet to lessen its flexibility in that region.

55 2. An eyeshield comprising a single flat expansive sheet of transparent flexible material constituting a body portion, the lower edge of said

sheet being shaped to fit the face below the eyes including a nose recess and cheek-conforming portions, retaining means secured to the lower outer edge for retaining the lower edge against the features to prevent the ingress of air between the shield and the face, means for retaining the upper portion of the shield away from the features to provide ventilation from the top, and a strip of leather stitched to the lower edge constituting a binding, said strip being slit at intervals to render it flexible and face-conforming.

3. A frameless, flexible eyeshield requiring contact with the features to be held in operative shape and in position, comprising, a flat expansive sheet of transparent material constituting the body portion, the lower edge of said sheet being shaped to include a nose recess and cheek-conforming portions adapting it to fit the face below the eyes on flexure into contact therewith, 20 said cheek-conforming portions being lower towards their outer ends than towards the middle of the shield, whereby the upper part of the sheet is buckled outwards when the lower edge is urged against the features, a head band for urging said lower edge against the features to hold the shield in operative shape and in position, retaining elements connected to the lower outer edges of said cheek conforming portions for upward or downward movement, the ends of said band being 25 secured to said elements thereby to permit adjustment of the points of suspension of the band in order to vary the angle of the shield to the face.

4. An eyeshield comprising, prior to application, a single flat expansive sheet of transparent flexible material constituting a body portion, the lower edge of said sheet being shaped to fit the face below the eyes including a nose recess and cheek conforming portions, retaining means secured to the lower outer edges of the shield below the top of the nose recess whereby, on application, the shield is tilted outwardly and forwardly toward its upper portion, and means reinforcing the upper portion against inward flexation.

5. An eyeshield comprising, prior to application, a single flat expansive sheet of transparent flexible material constituting a body portion, the lower edge of said sheet being shaped to fit the face below the eyes including a nose recess and cheek conforming portions, and retaining means secured to the lower outer edges of the shield below the top of the nose recess whereby, on application, the shield is tilted outwardly and forwardly toward its upper portion.

GRAY MILLER, JR.
